UNITED STATES PATENT OFFICE

WILLIAM J. VERONDA, OF SAN MARINO, CALIFORNIA

BOXING AMUSEMENT DEVICE

Application filed November 14, 1927. Serial No. 233,146.

My invention is a boxing amusement device especially designed for amusement parks, fairs, or the like, in which two figures are arranged to box with each other.

6 An object of my invention in a boxing amusement device is the arrangement of two figures simulating boxers and having electrically controlled mechanism to operate their arms to punch at each other and with 10 a manually controlled device so that two people called players may each operate his own boxer making the boxers approach and recede from each other, strike with the right and left hands when desired, and make partial turns to the right or to the left.

Another object of my invention is an arrangement by which if certain designated 20 blows are delivered by one boxer against the other, such boxer receiving the blows will be knocked out, that is, be knocked completely over.

In constructing my device I arrange a platform simulating a square boxing ring, with two figures representing boxers mounted on 25 small stands. By means of tracks and carriages underneath the platform and a slot in the platform, the boxers may be moved to and from each other by operators or players on opposite sides of the ring. I prefer to arrange this longitudinal movement by having 30 the carriages connected by a lazy-tong device with operating shafts so that by pushing and pulling on the shafts the lazy-tongs are contracted or extended, and the opposite ends 35 of such tongs being connected to each carriage, the carriages are moved longitudinally on the tracks and therefore cause the figures to approach and recede from each other.

In order to cause the figures to turn to the 40 right and the left they are each mounted on a vertical shaft extending upwardly through each carriage and through the slot in the platform, and each shaft engages in a socket in each of the stands, this socket preferably being square. By a train of gears, vertical 45 shafts are connected to the longitudinal shafts, actuating the lazy tongs so that on rotation of such control shafts, the boxers are turned in one direction or the other on the 50 vertical axis.

In the body structure of each of the figures there is a metallic framework having arms connected thereto and each arm is mechanically operated by an electro-magnetic device and there are two switches on each of the 55 operating wheels to control the blows struck by each of the boxers.

In order to give a knock-out I preferably arrange a series of switches, usually placing one on the chin and two on each side of each 60 figure. These are so arranged that after each switch is driven in by a blow, it remains in, but all the switches are required to be thrust in before a knock-out can be obtained. This is effected by dropping the vertical supporting 65 shaft which is released by an electro-magnetic controlled latch and forced downwardly by a spring. Therefore, practically at the same time that a blow is delivered which closes the last switch of the series on 70 one of the boxers, the supporting shaft is dropped and the figure topples on its base, requiring to be picked up and set by an attendant.

75 My invention will be more readily understood from the following description and drawings, in which:

Figure 1 is a perspective view of the ring, showing the platform, the two boxers thereon, each mounted on a stand, the slot in the 80 platform and the operating and control shafts.

Figure 2 is a perspective view of one of the boxers.

Figure 3 is a horizontal section on the line 85 3-3 of Fig. 4 in the direction of the arrows, showing the supporting carriages and the mechanism for operating the same underneath the platform.

Figure 4 is a vertical section substantially 90 on the line 4-4 of Fig. 3 in the direction of the arrows.

Figure 5 is an elevation of the framework supporting the boxer and the vertical section 95 through the carriage.

Figure 6 is a section on approximately the line 6-6 of Fig. 5 in the direction of the arrows through the framework of the boxer.

Figure 7 is a diagram of the electrical con- 100

trol for the electro-magnetic devices actuating the arms.

In the drawings a boxing ring is designated generally by the numeral 11, this preferably being made square except that the corners 12 are cut off to more readily accommodate the mechanism for operating the boxers. The ring has a platform 13 with a slot 14 therein. Each boxer is mounted on a stand 15 which has a conical part 16 terminating in the socket 17. This socket is preferably square for a purpose hereunder set forth.

The figure of the boxer is built up with a framework 18 having legs 19 connected as indicated at 20 to the platform 15. This frame is covered with a body structure 21 simulating a boxer and having suitable padding or such like, and whose arms are movable in the manner set forth hereunder.

Underneath the platform there are a pair of tracks 22 which extend from corner to corner of the ring and on these tracks there are mounted two carriages 23, each having wheels 24, the carriages being made of suitable light framework. Vertically positioned in each carriage there is a vertical shaft 25 preferably mounted in a sleeve 26, this shaft being made round for the major portion, but it is preferably square at the upper end 27 to engage in the square socket 17 of the stand. The vertical shaft has a reduced section 28 for latching, as hereunder set forth; and in addition a collar 29 to limit the downward movement of the shaft which is under a constant downward stress by the spring 30 coiled on the shaft and bearing between a washer 31 and the bottom of the carriage (Figs. 5 and 6).

The boxers are rotated by means of a horizontal beveled gear 31 which is keyed or splined to the vertical shaft 25 to allow a sliding movement of such shaft. This gear meshes with an idler gear 32 mounted on a cross shaft 33, supported on a suitable frame 34 in the carriage. This latter gear meshes with a gear 35, one of which is splined on each of the operating control shafts 36, which are slidable longitudinally through each of the carriages and out through the associated corner of the ring. Each of these operating shafts has a journal 37 in a bracket 38 secured to the base of the ring, and in a journal flange 39 mounted on the corner structure 12 of the ring and on each of these shafts there is an operating or control wheel 40 (note particularly Figs. 1, 3 and 4). It will be noted, therefore, that on turning each of the hand wheels 40 the control shafts 36 may be rotated either one way or the other and motion transmitted to each of the vertical shafts 35 to rotate these and hence the stands and the boxing figures.

It will be noted that the stands are supported elevated slightly above the platform

13 (see Figs. 5 and 6). Each of the figures is supported in this elevated position by means of a spring pressed detent 41 which engages in the reduced section 28 of each of the vertical shafts and holds the figures up. This detent is slidably mounted in a bracket frame 43 and is operated upon by a solenoid 44 also mounted in the carriage. This solenoid is connected to wiring, as hereunder described.

The mechanism for moving the figures toward and from each other comprises a pair of lazy-tongs 45, each set of tongs having one end pivotally connected at 46 to the carriage, and the other end pivotally connected to a brace 47 attached to the end 12 of the ring. A pair of collars 48 are attached to each of the operating shafts 36 and the central collar 49 positioned therebetween; this collar is connected by a vertical pivot pin 50 to a pair of cross links 51 of the lazy-tongs. Each of the carriages has a spring bumper 52, these bumpers being designed to engage when the carriages are thrust towards each other.

The shafts 36, besides being rotatable, are longitudinally slidable through the carriages and the gears 35, as above mentioned. Hence, when each shaft is moved, it elongates the lazy-tongs when thrust in, and contracts the lazy-tongs when pulled out. This action moves the carriage in towards the center of the ring from a corner or draws it back from the center towards the corner; thus the operator or player may control the movement of his boxer towards and from the other boxer and as above mentioned; and by turning the hand wheel 40, each operator may slightly turn his boxer a partial turn to the right or to the left.

The construction of the boxer's arms and manipulation thereof is substantially as follows, having reference particularly to Figs. 5 and 6: A cross frame bar 55 is connected to the upper portions 56 of the bars forming the frame 18, and from these there are short struts 57 at each side and a center strut 58. Each of these side struts supports a nipple 60 and the center strut a nipple 61. In each of these side nipples and the center nipple there is journaled a rock shaft 62, such shafts also having journals 63 in the T construction at the upper end of the posts 56. Arm rods 64 are adjustably connected to each of the rock shafts 62, these conforming somewhat to a person's upper and forearm, and have knobs 65 on the end to which are secured boxing gloves 66.

Connected to each of the rock shafts between the nipples 60 and 61 there are clamping collars 67 which have rock levers 68 connected thereto. Each of the rock levers has a plunger 69 slidably mounted in the solenoid mountings 70, each of these mountings being swivelly connected to a cross bar 71 connecting the leg frames 19.

A cable 72 having electric lead wires therein passes upwardly through the figure, preferably adjacent one of the leg frames, and there is a lead to each of the solenoids. The cable passes downwardly through an opening 73 in the stand and leads through the slot 14. These wires are sufficiently loose to allow the figures to topple over, as hereunder described, and to follow the motion of the carriages.

The wiring diagram to operate the solenoids is indicated in Fig. 7, in which there are windings 74 for each of the solenoids, there being leads 75 to each of the solenoids, a return lead 76 from each solenoid connected to a common return 77.

Mounted on each of the control wheels there are a pair of push button switches 78, each having a common lead 79 to a source of current supply, and each push button being connected through one of the leads 75 to a solenoid. It will therefore be seen that by pressing either of the push buttons, the solenoids may be operated, and when energized attract the armatures connected to the plungers 69, thus actuating either of the rock shafts 62 to swing the arms 64 and deliver a blow. Therefore, by pressing one switch after the other, the operator may cause his boxer to deliver right and left hand blows in rapid succession, or by operating only one switch he can cause the boxer to deliver blows with one arm only.

The mechanism for causing the knock-out is substantially as follows, having reference to Figs. 5 and 7, with the wiring diagram in connection with Fig. 5: This wiring diagram shows a source of power 80 having a lead 81 therefrom. On one side of the figure there is what might be called a lower right switch 82, an upper right hand switch 83, a chin switch 84, an upper left hand switch 85 and a lower left hand switch 86. There is a lead 87 from one side of the switch 82 to one side of the switch 85 and another lead 88 from the other side of the switch 82 to the opposite side of the switch 85 connecting into the lead 89, joining the switches 84 and 85. There is also a lead 90 connecting the switches 83 and 84 and a lead 91 from one side of the switch 83 to one side of the switch 86, and another lead 92 from the other side of the switch 83 to the opposite side of the switch 86 connecting into a lead 93, which lead 93 connects to one end of the solenoid coil 44. The other end of the solenoid coil is connected to a lead 94 which leads back to the source of power.

These switches 82, 83, 84, 85 and 86 are of a type which, when pressed in as by a blow, remain in, leading the circuit through the switches, and these may be reset in any suitable manner by an attendant. For instance I may utilize standard switches which may

be mechanically set by an attendant or switches which may be electrically set by the attendant. The switches are arranged on opposite sides of the body and one on the chin so that at least three blows on the switches are necessary to energize the solenoid 44 and retract the detent 41 so that the vertical shaft 25 may drop downwardly, hence releasing the stand from the supporting shaft 25 and in the circuit shown it is necessary that one of these blows be delivered on the chin.

The circuits and operative switches may be traced as follows: Presuming a blow is struck which drives in the switch 82, then the circuit leads from 81 through the switch 82, leads 88 and 89 to the chin switch 89 which it is presumed has been driven in. Presuming another blow has been struck on the right hand side driving in the switch 83, then the circuit from the switch 84 involves the lead 90, switch 83, leads 92 and 93 to the solenoid 44, thus energizing this solenoid; or if switch 83 is open the circuit would be through the leads 90 and 91 to one side of the switch 86, and if this switch should be closed by a blow on the left hand side, there will be a connection to the lead 93 and hence to the solenoid 44.

Presuming that the switch 82 is open and the switch 85 has been closed by a blow, then the circuit will be through the leads 81 and 87, through the switch 85, lead 89, through the chin switch 84, which must be closed, and lead 90. This circuit may then be completed either through the switch 83 being closed and the leads 92 and 93, or by the switch 86 being closed through the leads 91, switch 86, and lead 93. It will thus be seen that the solenoid 44 may be energized by two blows on the same side closing the switches or by a blow on opposite sides closing either opposite upper or opposite lower switches. This arrangement prevents an operator or player, when he thinks that his boxer has had one switch closed, from keeping that side of the boxer to his opponent, as it is immaterial whether the corresponding switch on the same side is closed or whether the proper switch on the opposite side is closed to complete the circuit to the solenoid 44.

As above mentioned, when the solenoid 44 is energized the shaft 25 immediately drops, allowing the boxer and the stand to drop slightly onto the platform 13 and the force of the blow which has been struck the boxer is sufficient to topple him over, thus effecting a knock-out.

In order to give amusement to the device, a push button 95 is illustrated in the chest of the boxer and this is designed to be connected to a Klaxon or other type of horn or some noise emitting device.

It will be readily seen, therefore, that I have invented an amusing device which re-

quires considerable skill in its operation and gives the opposing operators a chance to exercise their skill in what might be termed a competition, as each operator may advance and draw back his boxer in accordance with the progress of the boxing match and he may shift the boxer angularly either to the right or left in order to avoid or make blows more effective; and can operate the arms to strike blows in any desired order, repeating blows with the same arm if desired. In addition, it is desirable that the places where the switches are located should be indicated on the body of the boxers so that the operators will know where to have their boxers aim their lows.

These boxers if desired may be full size or nearly full size, and an attendant may call out the different blows and give points for the most skillful boxing, so that if one boxer does not receive a knock-out the attendant acting as umpire can designate which boxer wins the match. After a boxer receives a knock-out it is necessary only for the attendant to pull upwardly on the upper end of the vertical shaft 25 and to lift the boxing figure frame, fitting the socket 17 on the upper end 27 of the vertical shaft, with the boxer facing in the desired direction.

Various changes may be made in the principles of my invention without departing from the spirit thereof, as set forth in the description, drawings and claims.

I claim:

1. An amusement device comprising in combination a pair of figures simulating boxers, means to move said figures at the will of operators relative to each other, means to operate the arms of such figures to simulate boxing, an electrically controlled sustaining means to hold said figures erect, a plurality of electric switches disposed about the surface of said figures, and circuits associated with said switches to operate said electrically controlled means after certain of said switches have been actuated by blows thereupon.

2. An amusement device comprising a pair of figures representing boxers, a pair of rotatable and longitudinally slidable shafts, means operatively connected between each shaft and a figure to shift the figures towards and from each other on longitudinal movement of the shafts and to rotate each figure on a vertical axis on the rotation of each shaft, and means to actuate the arms of each figure.

3. An amusement device, as claimed in claim 2, the means to actuate the arms comprising pivotally mounted arm structures on each figure, electro-magnetic means to actuate each arm of each figure, a pair of electric switches operatively connected to each of the slidable shafts, and circuits from said switches to the electro-magnetic devices in

the boxer controlled by the shaft, whereby each operator may control the actuation of the arms of each figure as well as advance and retard and rotate each figure.

4. An amusement device comprising in combination a pair of vertical shafts, a figure representing a boxer mounted on each of said shafts, a pair of horizontal shafts slidably and rotatable, means operated by the sliding movement of the horizontal shafts to move the vertical shafts and the figures to and from each other, means actuated by rotating the horizontal shafts to rotate the vertical shafts and thereby the figures, means carried by the horizontal shafts for moving the arms of each figure simulating boxing, at least one of said figures having a plurality of electric switches, some of said switches being in a circuit to operate in series, electro-magnetic means controlling the position of the vertical shaft for such figure, said switches being actuated on receiving blows from the other figure, and a circuit associated with said switches for energizing the electro-magnetic means and operating the vertical shaft to allow the figure to fall.

5. An amusement device comprising in combination a fixed structure, a pair of movable carriages associated therewith each having a vertical shaft mounted therein with a figure demountably supported on each shaft, a horizontal shaft slidably and rotatably movable relative to each carriage, a lazy-tong connected to each horizontal shaft and to each carriage and the fixed structure, whereby the longitudinal movement of each shaft operates the lazy-tong connected therewith to shift the carriage, a gear train interconnecting the horizontal and the vertical shaft of each carriage to rotate the vertical shaft on rotation of the horizontal shaft and thereby rotate the figure, each figure having a pair of pivotally mounted arms, an electro-magnetic device connected to each arm to actuate same, simulating boxing, and a circuit with a switch for each electro-magnetic device.

6. An amusement device, as claimed in claim 5, said vertical shafts being vertically slidable to demount the associated figures therefrom when lowered, each figure having a plurality of electric switches, some of said switches being arranged for linking in a series circuit, an electro-magnetic device supportingly connected to each vertical shaft, said device being in circuit with the switches and said switches being operated on receiving blows from an opposing figure, the energization of the electro-magnetic device allowing dropping of the vertical shaft and detaching of the figure supported thereby to allow such figure to fall.

7. An amusement device comprising in combination a pair of vertical shafts, each having a figure representing a boxer de-

mountably secured thereon, means to move said shafts toward and from each other and to rotate the shafts thereby moving and rotating the figures, said moving and turning
5 means being independently controlled, independently controlled means to actuate the arms of each of the figures to simulate boxing, and control means carried by one of said figures and adapted to be actuated by receiving a predetermined blow from the other figure to retract the shaft supporting the figure and allow it to fall.

In testimony whereof I have signed my name to this specification.

15 WILLIAM J. VERONDA.
